UNITED STATES PATENT OFFICE.

JESSE M. HARR, OF BALTIMORE, MARYLAND.

SEESAW.

SPECIFICATION forming part of Letters Patent No. 308,962, dated December 9, 1884.

Application filed April 5, 1884. (No model.)

To all whom it may concern:

Be it known that I, JESSE M. HARR, of Baltimore, in the State of Maryland, have invented a new and useful Improvement in Seesaws, of which the following is a full, clear, and exact description, reference being had to the annexed drawings, forming part of this specification.

This invention consists of an improvement 10 by which the seats of a seesaw are kept horizontal and the operation of the device rendered easy, to adapt it for use by very young children, as hereinafter described and claimed.

In the drawings, Figure 1 is a side elevation 15 of my improved seesaw. Fig. 2 is a longitudinal vertical section, and Fig. 3 a plan view, of the same.

A indicates a stand or supporting-frame, in the top of which are pivoted the connected oscillating beams B.

On the ends of the beams B are vertical standards C, between which are pivoted the chairs D.

In the stand A, below the beams B, is also 25 pivoted a lever, E, the ends of which are pivoted to the lower ends of arms F, attached to the backs of the chairs and extending down below the beams B. The lever, E is formed with a downward-extending projection, G, at 30 its center, and its pivot H passes through the lower end of this projection. With this construction, when the beams B are oscillated, the lever E will be oscillated by means of its connection with the chairs, and the said lever will in turn oscillate the chairs to keep 35 them in a horizontal position by means of its traversing movement due to the location of its pivot.

On the ends of the lever E are mounted 40 treadles or carriages I, consisting of foot-braces pivoted at their outer ends to the projections or arms F at points between the chairs D and ends of lever E, and supported on the lever E by means of rollers J. With this construction, as either chair is elevated by the 45 oscillation of beams B, the lever E and the treadle connected to said chair move inward toward the center of the beams, so that if the occupant of the chair braces himself against 50 the treadle he can drive the treadle inward

toward the center, and thus cause his end of the beam to rise by the exertion of muscular force. Where the chairs are balanced against each other by occupants of equal weight a very slight pressure on the treadles in turn 55 will cause the seesaw to move with great ease. Where the occupants of the chairs are not of equal weight, they may be balanced against each other by means of adjustable weights K, arranged in any obvious manner. Such weights 60 K may be attached to adjustable bars L, adapted to slide in supports at one side of the seats, which bars are to be so arranged that they may be adjusted properly by the occupants after they are seated.

To the stand A are attached steps or ladders M, leading up to a platform, M', or to the chairs, and to the platform or ladders are pivoted vertical levers N, having shoulders O, adapted to engage with the under side of one 70 of the beams B, to prop and support the seesaw in a horizontal position while persons are being seated in the seesaw or descending therefrom. The handles of the said levers are to extend up near the chairs, so that they can 75 be operated therefrom.

Instead of using two beams B, connected together at the ends, as shown, a single beam may be used for supporting the chairs.

P P represent cushion-springs attached to 80 the lower ends of arms F, and adapted to be compressed in turn, to break the jar when said arms strike the ground. Springs may also be located on the stand A, to connect the beams B elastically therewith in such manner that 85 the springs will be alternately compressed or expanded by the oscillation of the seesaw, to prevent jarring and to increase the ease of operation.

Q indicates a girder attached to the beam 90 or beams B in a well-known manner, to give the required strength where said beam is made light.

Where a number of seesaws are to be used, as on pleasure-grounds, a long platform may 95 be constructed, alongside of which the seesaws may be arranged.

What I claim is—

1. The combination, with the chairs of a seesaw, of a traversing lever for keeping the chairs 100

in horizontal positions during the movement of the same, substantially as shown and described.

2. The combination, with the oscillating beam or beams of a seesaw and the chairs or seats supported on the same, of a traversing lever pivoted below said beams and connected to said chairs at its ends, substantially as shown and described.

10 3. The combination, with the oscillating beam or beams of a seesaw and the chairs supported on the same, of a traversing lever pivoted below said beams and having its ends connected to arms projecting downward from the 15 chairs, and the treadles or carriages supported on said lever and pivoted to said arms between the chairs and said lever, substantially as shown and described.

4. The combination, with the oscillating beam or beams of a seesaw, of adjustable 20 weights attached to or connected with the ends of said beams, and springs adapted to be compressed in turn, substantially as and for the purpose set forth.

5. The combination, with the oscillating beam or beams of a seesaw, of adjustable props 25 or levers for supporting said beam or beams in a horizontal position, substantially as and for the purpose set forth.

JESSE M. HARR.
